UNITED STATES PATENT OFFICE.

LEWIS T. WILCOX, OF PEEKSKILL, NEW YORK.

GRATE FOR OIL AND GAS STOVES.

Application filed January 22, 1927. Serial No. 162,691.

This invention relates to grates for oil and gas stoves and to the type of grates shown and described in Letters Patent No. 1,408,235 granted to me February 28, 1922 and more particularly to an improvement in the construction of grates as shown and described in my copending application, Serial No. 744-317 filed October 18, 1924.

The grates made in accordance with my present invention are constructed to include all the advantages of the form of grate as shown and described in my application aforesaid, and in carrying out the invention the grate made in accordance therewith includes a plurality of bars preferably made of band steel and each bent at one end portion thereof with the extremity of each bent end portion suitably connected to a part of the adjacent bar as will be hereinafter more particularly described.

In the drawing Figure 1 is a plan of a form of grate made in accordance with this invention.

Fig. 2 is an elevation of an end portion of one of the bars.

Fig. 3 is a section on line 3-3, Fig. 1.

Fig. 4 is a plan similar to Fig. 1 showing another form of the invention.

Fig. 5 is a plan also showing another form of the invention, and

Fig. 6 is also a plan showing a still further form of the invention.

Referring to the drawing and particularly to Figs. 1, 2 and 3, a grate for oil and gas stoves made in accordance with this invention may be constructed to include a plurality of band metal bars preferably made of steel and rectangular in cross section as illustrated at 10 and 11. The end portion of each of these band metal bars is bent so that its extremity forms a U or channel, the parts of which are designated at 12 and 13, 12 being the base of the channel and 13 the extremity of the bar. Each of the bars is similarly formed and in this structure there are six bars employed so that the angles between them are approximately 60° and the channel portions at the ends of each bar are formed accordingly so that the parts are assembled with the extremity 13 of each bar abutting against the adjacent portion of the next or adjacent bar and is riveted or bolted or otherwise connected thereto so as to provide a central opening of appreciable diameter but as small as possible at the centre of the grate.

The grate structure shown in Fig. 4 is similar to that illustrated in Figs. 1, 2 and 3, with the exception that eight instead of six bars are employed so that the angles between the bars are approximately 45° angles. The bars in this case are made of the same kind of metal and are indicated at 14 and 15. The end portion of each bar is bent to form a channel, the parts of which are designated at 16 and 17, 16 being the base of the channel and 17 the extremity of the bar. The extremities of the bars in this construction are welded to the adjacent portion of the next adjacent bar so as to provide a central opening of appreciable extent at the centre of the grate. Also as indicated in this structure, the length of alternate bars is greater than that of the intermediate bars, the extremities of the longer bars being indicated at 18 and 19 so that the grate is adapted to fit within a square opening in the upper portion of the stove instead of in a round opening as when the arms of the grate bars are all of equal length.

The form of the invention shown in Fig. 5 is also similar to that shown in Figs. 1 and 4, except that in this instance the end portions of each bar are bent to a substantially V shape. In this figure the bars are indicated at 20 and 21 and the bent extremities thereof at 22 and 23, 22 being an angle of the V and 23 the extremity of the bar. The extremity 23 of each bar is suitably connected to the adjacent portion of the next succeeding bar by being welded or otherwise connected thereto. In this structure the opening at the centre of the grate is relatively smaller than that in the types of the invention hereinbefore described.

In the form of the invention shown in Fig. 6, the adjacent grate bars are indicated at 24 and 25. The extremity of each grate bar is bent on itself at opposite angles, for example the end of the grate bar 24 is so bent at one end as to provide a portion 26 at one angle thereto and a portion 27 at an opposite angle thereto. In this structure as clearly illustrated in this figure, the extremity 27 of the bar 24 is adapted to abut against and to be connected to the portion 28 of the next adjacent bar 25 by being welded or riveted or otherwise connected thereto, each of the bars being similarly connected to the next adjacent bar so as to form an opening of appreciable extent at the centre of the grate.

In each of the forms of the invention as hereinbefore described, the outer extremity of each of the grate bars is notched as indicated at 29 in Figs. 2 and 3 in order to 5 permit the grate bar to fit within and rest upon the upper portion of the oil stove in which it is adapted for use in the customary manner.

I claim as my invention:

- 10 1. A grate bar for oil and gas stoves and the like, comprising a plurality of metal bars each having a bent end portion with the extremity of the bent end portion of each bar connected to an adjacent portion 15 of the next adjacent bar.
2. A grate bar for oil and gas stoves and the like, comprising a plurality of band metal bars of rectangular cross section each having a bent end portion with the extremity of the bent end portion of each bar abutting against and connected to an adjacent portion of the next adjacent bar.
- 20 3. A grate bar for oil and gas stoves and

the like, comprising a plurality of metal bars each having a U shape bend at one end thereof with the extremity of the U shape bend at the end of each bar connected to an adjacent portion of the next adjacent bar.

4. A grate bar for oil and gas stoves and the like, comprising a plurality of band metal bars of rectangular cross section each bar having a U shape bend at one end portion thereof with the extremity of the U shape bend of each bar connected to an 30 adjacent portion of the next adjacent bar.

5. A grate bar for oil and gas stoves and the like, comprising a plurality of band metal bars each having a U shape bend at one extremity thereof with the end of the U shape bend of each bar abutting against and welded to an adjacent portion of the 35 next adjacent bar.

Signed by me this 17 day of January, 1927.

LEWIS T. WILCOX.
